CARTRIDGE FEEDING MECHANISM FOR
AUTOMATIC FIREARMS

George Webb, Hartford, and William L. Swartz,
West Hartford, Conn., assignors to Colt's Manufacturing Company, a corporation of Connecticut

Application August 14, 1943, Serial No. 498,624

6 Claims. (Cl. 89—33)

1

This invention relates to improvements in the feeding mechanism which coacts with a cartridge holding feeder such as used with automatic firearms to move said feeder through the feed channel of the firearm.

The improvements in the feeding mechanism of the firearm, while not to be so restricted, are primarily applicable to firearms of the type illustrated and described in Browning Patent 1,525,065 and in co-pending application, Serial No. 325,405, filed March 22, 1940, in the name of George Webb, now Patent No. 2,375,452. The magazine shown and described in connection with the present invention is in many respects similar to the magazine illustrated in co-pending application, Serial No. 380,437, filed February 25, 1941, in the name of George Webb, now Patent No. 2,375,453.

Automatic firearms of the type illustrated in Browning Patent 1,525,065 and Webb Patent 2,375,452 were originally primarily designed to use rigid feeders each holding a relatively few cartridges. Some of said feeders were designed to accommodate five cartridges while others accommodated as many as ten. Said firearms were also found to operate satisfactorily with flexible feeders containing as many as fifteen cartridges and adapted to be disposed in a magazine accommodating said flexible feeder and cartridges. Such a magazine is disclosed in the said Webb Patent 2,375,452, and in the Webb Patent 2,382,926, which was issued on application, Serial No. 437,850, filed April 6, 1942, the said application being a division of the application on which was issued Patent 2,375,452.

When automatic firearms of the type described in said patents were used in airplanes, it was found desirable to develop magazines containing relatively greater numbers of cartridges than were contained in the feeders and magazine referred to in the foregoing, due to the fact that the magazines attached to the firearms mounted in airplanes could not be readily reloaded in flight and, when the magazine of said firearm was exhausted of cartridges, the airplane had to be grounded before the magazine could be reloaded. These circumstances led to the development of the magazine illustrated in the said Webb Patent 2,375,453, which is an endless belt type of magazine primarily but not restrictively adapted to contain approximately thirty cartridges. Furthermore, the last said magazine was also primarily adapted to contain cartridges or rounds of such size as to develop a muzzle velocity of approximately 2,000 feet per second

2

and the construction embodied in said magazine and the feeding mechanism of the firearm operate satisfactorily when using ammunition of the size mentioned. Said firearms and magazines last above referred to were also primarily designed to use caliber 37 mm. ammunition although the principles embodied in said various inventions are not necessarily to be restricted to use with ammunition of said caliber.

10. Firearms of the type referred to in the foregoing are also well adapted for anti-aircraft use from the ground but in order that said firearms might be more effective when used for such purposes, it was found advantageous to adapt the firearms and magazines to use ammunition provided with projectiles of greater mass and having correspondingly heavier charges to produce a muzzle velocity for said projectiles of approximately 3,000 feet per second. This type of ammunition was materially larger in size and greater in weight than the 2,000 foot per second type ammunition described in the foregoing. The larger size cartridges, while requiring some re-designing of the firearm illustrated and described in said Browning Patent 1,525,065 and said Webb Patent 2,375,452, required material changes in the construction of a magazine of the type illustrated in said Webb Patent 2,375,453, when adapted to contain a relatively large number, such as thirty or more, of the larger size cartridges. The need for such changes was due primarily to the additional weight of the larger size cartridges.

The general object of the present invention is 35 to provide a feed mechanism adapted to be used with and as a part of the improved magazine for the larger cartridges above referred to.

A more specific object of the present invention is to provide a feeder engaging stop pawl mounted adjacent or in the magazine and adapted to supplement the function of a stop dog embodied in the feed box of the firearm on which the magazine is mounted.

A further specific object of the invention is to 45 provide a feeder engaging holding pawl carried by the feed slide of the firearm to prevent relative movement between the feed slide and feeder while moving in feeding direction, whereby the possibility of over-feeding of the feeder during such feeding movement of the feed slide is substantially eliminated.

The details and other objects of the invention will be described in the following specification and illustrated in the accompanying drawings. 55 The accompanying drawings show the embodiment

ment of the invention which is deemed preferable, but it will be understood that the drawings are intended for illustrative purposes only and are not to be construed as defining or limiting the scope of the invention, the claims forming a part of this specification being relied upon for that purpose.

In the drawings, Fig. 1 is a rear end elevation of a firearm and a magazine embodying the principles of the present invention, said view being partly broken away to expose details.

Fig. 2 is a sectional plan view of said magazine mounted on a fragmentary portion of the firearm, said view being taken substantially on the line 2—2 of Fig. 1.

Fig. 3 is a side elevation of the magazine viewed from the right hand side, said magazine being mounted on a fragmentary portion of the firearm and portions of the magazine are also broken away to better illustrate details thereof.

Fig. 4 is a side elevation similar to Fig. 3 but showing the magazine viewed from the left hand side.

Fig. 5 is a fragmentary sectional vertical elevation taken on line 5—5 of Fig. 2 and illustrating the means embodied in the present invention for controlling the movement of the feeder.

Fig. 6 is a view similar to Fig. 5 but illustrating the feeder control means in different positions from those illustrated in Fig. 5.

Fig. 7 is a fragmentary plan view taken on the line 7—7 of Fig. 5. Fig. 7a is a detail view of some of the parts shown in Fig. 7.

Fig. 8 is an enlarged fragmentary side elevation of the ends of the feeder which are connected together to form an endless feeder.

Fig. 9 is a sectional elevation of the feeder connecting means taken on the line 9—9 of Fig. 8.

Fig. 10 is a detail end elevation on the same scale as Figs. 8 and 9, showing the feeder and the supporting means therefor in the feed channel.

As stated in the foregoing, the firearm illustrated in the present drawings operates satisfactorily to automatically fire cartridges of said larger size which, when fired, develop a muzzle velocity of approximately 3,000 feet per second. However, a magazine of the type shown in said Webb Patent 2,375,453, when adapted to accommodate thirty or more of such larger size cartridges, presents conditions which produce misfunctions in the operation of the feeder control pawls which are normally provided in the feed box of the firearm. Said conditions arise primarily from the substantially increased weight of the rounds carried by the magazine and particularly when about half of the rounds originally carried by the fully loaded magazine have been fired so that the magazine is only partially loaded. Under these conditions, the cartridges remaining in the magazine are disposed substantially entirely on one side of the magazine and, under normal conditions, are positioned above the feed channel whereby the force of gravity acts upon the increased mass or weight of the larger size cartridges to effect, at times, undesired feeding of the remaining cartridges to the feed channel of the firearm. Said force of gravity is greatly accented particularly when the firearm and magazine are mounted in an airplane and the airplane, for example, is levelling off from a power dive. Forces of gravity are frequently encountered, during such maneuvering, amounting to eight or ten times the normal force of gravity, for example.

In order that cartridges of said larger size

may be satisfactorily fed to and fired by the firearm herein illustrated, the magazine as shown and the herein-described and illustrated improvements in the feeding mechanism of the firearm were developed. Said magazine and improvements in the feeding mechanism of the firearm primarily constitute additions to the feeder control mechanism normally provided in the firearm described particularly in said Webb Patent 2,375,452, whereby when the instant magazine is removed from the firearm, said firearm will nevertheless properly function with feeders or magazines containing smaller numbers of cartridges than the instant magazine. In other words, the additional feeder control mechanism rendered necessary by using the instant magazine is, for the most part, carried by said magazine, whereby a minimum of conversion of the firearm is required in order to adapt said firearm for use with said other types of feeders and/or magazines.

Referring to the drawings, the automatic firearm 10 has a breech casing 12 which is surmounted by a feed box 14 provided with a cover 15 hingedly connected to one side thereof. The feed box 14 is provided intermediately of the ends thereof with a feed channel 16 extending substantially horizontally and transversely to the longitudinal axis of the firearm. The entrance 18 and the exit 20 of the feed channel are respectively provided in opposite side walls of the feed box 14.

A magazine generally designated 22 and having a generally arcuate configuration is shaped similarly to the magazine illustrated in said Webb Patent 2,375,453. In a number of respects, the instant magazine embodies principles similar to those illustrated and described in the last said patent. Basically, the instant magazine comprises a front or forward end wall or member 24 and a rearward end wall or member 26 spaced from said front member longitudinally of the major axis of the firearm. Said end members are respectively substantially planar and are each provided with a plurality of apertures such as indicated at 28, 30 and 32, the peripheries of which apertures are spaced inward from the outer periphery of the magazine except that aperture 30 extends through the lower portion of each end member to provide an opening 34 therein adapted to receive the feed box of the firearm. The apertures 28, 30 and 32 are provided principally to reduce the weight of the end members and also render readily accessible certain elements embodied within the magazine. Said apertures are separated by vertically disposed struts 36 which are preferably T-shaped in cross section, as indicated in Fig. 2, to strengthen said struts. Horizontally disposed struts 38 are also provided for purposes to be described.

The feed box cover 15 is provided with a leaf-spring latch 39 adapted to engage the rib on one of the struts 36, which rib is afforded by the T-shaped formation of said strut, to releasably maintain said cover in vertical or raised position.

In the preferred embodiment of the invention, the end plates 24 and 26 are each bipartite, the respective parts of the rearward end member being designated A and B and those of the forward end member being designated A' and B'. The respective parts of each bipartite end member are also respectively provided with overlapping portions 40 and 42 which are respectively provided with aligned apertures to accommodate a quick

detachable locking mechanism 44 comprising a split pin 46 having resilient and shouldered legs adapted to cooperate with an annular collar 48. The locking mechanism secures the uppermost and overlapping portions of the two parts of the magazine end members together when the magazine is attached to the firearm, one locking mechanism being provided for each end member.

As previously stated, the opening 34 in the lower portion of the magazine accommodates the firearm and particularly the feed box. The portions of the lower part of each end member disposed immediately on opposite sides of said opening 34 are adapted to be respectively secured to the opposite sides of the feed box by quick detachable means similar to those disclosed in said Webb Patent 2,375,453. Said quick detachable means comprise a pair of brackets 50 secured to the right side of the feed box, said brackets being apertured to receive a headed pin 52 which also extends through suitable apertures provided in the end members 24 and 26 to accommodate said pin. If desired, the rearward end of said pin may be longitudinally grooved for a portion of its length to receive a resilient holding or locking member 54 which detachably maintains said pin in operative position.

The left side of the feed box is provided with a plurality of laterally projecting notched pins 56 which are beveled at their outer ends and adapted to be held in operative position on said side of the feed box by a pair of spaced plates 58 respectively disposed outward of the ends of entrance 18 of the feed channel. Said plates 58 are apertured to receive said pins 56 and are secured to said feed box side by suitable means such as rivets. The portions of the end members 24 and 26 immediately adjacent the feed box are also respectively provided with brackets 62 each having a pair of spaced bearing blocks 64 each accommodating a vertically slidable pin 66 which carries a pair of spaced notched locking blocks 68 each beveled at one end and adapted to respectively coengage with the beveled and notched pins 56 to detachably secure said adjacent portion of the magazine to said left side of the feed box.

The end members 24 and 26 are held in suitable spaced relationship by a plurality of headed spacing rods 70 whereby the assembled bipartite end members are removable from and attachable to the firearm as units each comprising a bipartite portion of the entire magazine. When securing said units to the firearm, the unit comprising end member parts A and A' is affixed to the right side of the feed box by pin 52 and the unit comprising end member parts B and B' is affixed to the left side of the feed box by moving the lower portion thereof horizontally to pass the pins 56 through the apertures therefor in bracket 62, following which the beveled ends of notched blocks 68 coengage with the beveled ends of the pins 56 to cam the locking blocks 68 into respective engagement with the notches of pins 56 to secure said unit thereto. Pins 66 are normally respectively biased by springs 72 to urge the locking block 68 upward into engagement with the pins 56. Disengagement of the blocks 68 from the pins 56 is effected by pressing downward a button 76 fixed to the upper end of each pin 66.

After the respective units have been thus secured at their lower portions to the opposite sides of the feed box, the upper portions of said units are secured by the quick detachable locking mechanism 44.

The end members 26 and 24 are also respective-

ly provided with inwardly projecting flanges 77 and 78, each of which have a curved configuration similar to and substantially coextensive with the outer periphery of the end members. Said flanges 77 and 78 are respectively disposed inward from the outer periphery of their end members a substantially even distance and are also adapted to respectively engage the bases and noses of cartridges to be carried by the magazine. In effect, the flanges and end plates thus comprise a generally curved cartridge guideway which opens outward of the magazine. Said cartridges are diagrammatically designated 80 in Figs. 5 and 6.

The magazine is also provided with a cartridge feeder guideway or guide channel 82 which is generally arcuate and corresponds to the configuration of the outer periphery of the end members except that the periphery of the guideway is disposed inward from the periphery of said end members a substantially even distance. The guideway 82 includes a plurality of arcs having different radii. Each of the two portions of the guideway spaced outermost or farthest horizontally from the feed box comprises an arc having a smaller radius than that of any other portion of the guideway. The bases of said outermost arcuate portions of the guideway are respectively coincident with the peripheries of two reels 84 and 86 each consisting of a pair of spaced discs 88 and 90 and the discs of each pair being joined by a plurality of spacing rods 92 and 94.

The reels 84 and 86 are respectively provided with apertured hubs 96 and 98 which are respectively pivotally mounted on two substantially parallel shafts 100 and 102. The opposite ends of the shafts 100 and 102 are supported in apertures 104 and 106 provided in the outermost vertical struts 36 of the end members and are held in operative position by suitable cotter pins, as is clearly shown in Figs. 1 and 2. The horizontal struts 38 serve to brace said vertical struts 36 to more rigidly support the apertured portions thereof which receive the shafts 100 and 102.

The reels 84 and 86 are substantially identical in construction except that reel 83 is provided with an annular narrow drum 108 which is disposed between the spaced discs 90 a short distance inward from the peripheries thereof. The drum 108 is for purposes to be described.

A pair of parallelly spaced arcuate plates 110 are respectively disposed in the planes of and above the spaced discs 88 and 90 of the reels, the outermost edges of said plates defining the bottom of that portion of the guideway 82 which is above said reels. Said plates 110 are suitably apertured to receive and be supported by those spacing rods 70 which are disposed in the upper portion of the magazine. Said plates are also severed intermediately of their ends at the juncture defining the abutting portions of the two bipartite parts of the magazine to permit separation of said parts when desired. The underside of each outermost end of said plates 110 is tapered inward as indicated at 112 in Fig. 1, whereby the outer edges of said plates terminate adjacent and substantially tangentially to the peripheries of the discs comprising the reels 84 and 86.

The sides of the guideway 82 are respectively defined by a pair of parallel spaced arcuate plates 114 and 116 respectively disposed in spaced relationship to the outer sides of the plates 110 and the reels 84 and 86. The arcuate outer peripheries of said plates 114 and 116 project outward

a short distance beyond the outer peripheries of the plates 110 and the reels 84 and 86, whereby all of said plates and reels cooperate to form a channel-like skeleton guideway opening outward of the center portion of the magazine and adapted to receive a flexible articulated-link feeder to be presently described. The arcuate configuration of the plates 114 and 116 is similar to that of the end members 24 and 26 and said plates are supported by the plurality of spacing rods 79 and shafts 100 and 102 which rods and shafts are received in suitable apertures provided in said plates. Said plates and end members are maintained in proper spaced relationship by hubs 96 and 98 of the reels and spacing sleeves 118 which surround rods 79, 100 and 102, between said plates and the end members 24 and 26. Plates 114 and 116 are also medially severed at the juncture defining the abutting portions of the two bipartite parts of the magazine. Said plates are further provided with a plurality of weight reducing apertures 117. It will also be noted that the lower edge of each plate 114 and 116 is also substantially straight and extends inward substantially to the adjacent wall of the feed box 14 to prevent upward movement of the feeder.

The magazine is also provided with a plurality of curved foraminous plates 120 and 122 extending between and respectively disposed against the outermost edges of the end members 24 and 26, said plates preventing accidental movement of the cartridges from the feeder, to be described, when the feeder is moving around its guideway 82. Plate 120 has its inner end disposed adjacent to but spaced slightly from the right hand side of the feed box as clearly shown in Figs. 1 and 2. The sides of said inner end of the plate 120 are accommodated in a pair of opposed grooves 124 respectively formed in the end members 24 and 26. The outer end of plate 120 terminates slightly below the plane in which the shafts 100 and 102 are disposed and said outermost end is held in proper position against the outer edges of the end members by a pair of spaced leaf-spring latches 126 respectively provided with manipulating handles 128.

Plate 122 has its upper end projecting farther around the outer edges of the end members 24 and 26 than the upper edge of plate 120, as is clearly indicated in Figs. 1, 2 and 4. The lower or innermost edge of said plate terminates substantially at the point indicated 130 in Fig. 1. Said plate is secured to the outer edges of the end members 24 and 26 by a plurality of manually slidable latches 132 carried by said plate and adapted to be respectively received in apertured ears 134 carried by said end members. Said slideable latches 132 are preferably secured in locking position by spring-pressed buttons 136 movably carried by the plate 122 and adapted to engage the innermost end of each latch when in latching position. When buttons 136 are depressed inward, the latches may be moved from latching position.

A curved cylindrical tube 138, which alternatively may be a rod, is fixed to the interior surface of the plate 122 substantially opposite the guideway 82, as is clearly shown in Figs. 2 and 3. Said tube is adapted to engage a portion of the outer surface of each cartridge when moving around the guideway and the flanges 77 and 78 to prevent accidental movement of the cartridges outward of the feeder holding the same. In view of the cylindrical outer surface of the tube 138, a minimum of friction will be developed between

said tube and cartridges. The opposite ends of said tube are preferably tapered inward, as shown in Fig. 1, to facilitate the initial slideable engagement of each cartridge with said tube. Said tube also serves to render the curved plate 122 more rigid.

It will be apparent that both plates 120 and 122 are readily removable from the magazine to facilitate the loading of the feeder with cartridges. After the feeder has been loaded with the full number of cartridges to be carried thereby, said plates are fixed on the magazine in the position shown in Figs. 1 through 4.

To supplement the retaining of the cartridges within the feeder by plate 122 and tube 138, if desired, an auxiliary flange 139, shown in Figs. 5 and 6, may be formed on end member 24. Said flange 139 is curved and evenly spaced from the flange 77 to provide an arcuate groove between said flanges for slidably receiving therein the noses of the cartridges. It will thus be seen that the flange 139, which extends around said end member a distance substantially equal to the length of plate 122, will serve to prevent movement of the noses of the cartridges outward from the feeder when said cartridges are moving through the channel formed by flanges 77 and 139. If desired, end member 26 may also be provided with a flange similar to flange 139 for purposes of providing, in combination with flange 78, a groove adapted to receive the bases of the cartridges to prevent movement of the same outward from the feeder.

A horizontally disposed substantially flat plate 140 is disposed between the lower outer edges of end members 24 and 26 and is received in grooves 141 respectively provided in the inner surfaces of said end members, as is clearly shown in Figs. 4, 5 and 6. Said plate, in effect, comprises a continuation of the innermost or lower end of plate 122, plate 140 extending outward beyond said end of plate 122. A vertical rib 141' extending upward from plate 140 and parallel to end member 24 is adapted to engage the noses of cartridges to guide them in proper horizontal position to be fed to the feed channel of the firearm. It will thus be seen that plate 122, in conjunction with plate 140, serves to cover or close the outermost open face of the cartridge and feeder guideways and prevent movement of cartridges outward and downward from said guideways.

Plate 140 is also provided with a pair of spaced pivotally mounted dogs 142 adapted to project at their inner ends through suitable apertures 144 provided in plate 140. The dogs 142 are mounted on a horizontal shaft 146 carried by a pair of apertures respectively formed in the end members 24 and 26. Said dogs are also preferably integrally joined by a web 148 extending therebetween. The inner ends of the dogs are normally biased upward by a coil spring 150 surrounding shaft 146. Shaft 146 also pivotally supports an operating handle 152 disposed immediately of the dogs 142. The inner end of operating handle 152 is adapted to engage web 148 to move the inner end of said dogs downward when the outer end of said handle is moved upward. The purpose of dogs 142 will be presently described.

The guideway 82 is adapted to receive a flexible articulated-link feeder 154 which is fragmentarily illustrated in position in said guideway in Fig. 1 and is also shown in detail in Figs. 5 through 10. Said feeder is of a more simplified construction than that embodied in the feeder

shown in said Webb Patent 2,375,452, and comprises a plurality of pivotally connected U-shaped channel-like links 156, said links being arranged in end to end relationship to form a substantially flexible channel which is disposable around the guideway 82 in such position that said flexible channel opens outward. Said links are preferably formed of sheet metal and may be stamped from said metal in the form of blanks which are subsequently bent into channel shape as described. In view of this, said links may be more inexpensively manufactured than other links heretofore used for similar purposes. The opposite sides or legs 158 of the links comprise side flanges, each of which is provided with a cartridge receiving notch 160 extending inward from the outer edge of each flange.

The side flanges of said links are each provided at their opposite ends with outward extending or projecting ears 162. The ears extending from one end of each link are respectively offset outward a distance approximately equal to the thickness of the sheet-like material from which the links are formed, whereby said offset ears are adapted to be disposed in overlapping relationship with the non-offset ears on the adjacent end of the link to be secured thereto. Said overlapping ears are respectively provided with suitably aligned apertures 159 to receive rivets 164 which serve to secure the adjacent links together and provide pivots about which said links may relatively rotate a limited amount. Said apertures and rivets are disposed slightly above the horizontal medial line of the side flanges of the links, as viewed in Figs. 5 and 6, in order to economize in space required to accommodate the feeder when curved around the guideway 82.

The adjacent edges or ends of the base members 166 of the successive links are spaced from each other when the links are disposed in a substantially straight line, as is clearly shown in Figs. 5 through 8. Said spacing also extends downward between the upper portions of the adjacent edges of the side flanges of the links, as is clearly shown in Figs. 5, 6 and 8, for purposes to be described. Said adjacent edges of the ends of base members 166 are also provided with substantially shallow rectangular notches 168 to provide, in conjunction with the other space between the edges of base members 166, an opening comprising a feed recess 170 adapted to receive feeder movement controlling pawls to be presently described.

Each link 156 is also provided with a U-shaped spring 172 adapted to releasably hold a cartridge within the spaced notches 160 provided in the side flanges of each link. The cartridges 80 are mounted within the feeder by merely snapping the same into the notches 160, against the action of the outer ends of the springs 172, said outer ends of the springs being shaped to engage the cylindrical surfaces of the cartridges after they are properly seated within the notches 160 to releasably hold the cartridges therein.

After a feeder of the proper length has been fabricated by pivotally joining the correct number of individual links, the ends of said feeder are adapted to be joined by quick detachable securing means illustrated in detail in Figs. 8 and 9 to thus form an endless feeder disposable in the guideway 82 and extending around the magazine as outlined by dotted line 173 in Fig. 1. The end links which are joined by said quick detachable means are shaped no differently from the other links. However, upon the alignment of the aper-

tures 159 respectively in the ears of said links, a headed pivot pin 174 is inserted in each pair of aligned apertures rather than pivotally secure said ears by rivets. Said pivot pin is preferably tapered at one end, as clearly shown in Fig. 9, and the head 176 on the other end has a diameter larger than the apertures 159 to limit the movement of said pivot pin therethrough. The end of the pivot pin adjacent the head 176 is formed with a reduced diameter to provide an annular groove 178 for purposes to be described.

The ears 162 extending from one end link are each provided with a pivot pin locking member 180 which is pivotally secured to the ear by a headed pin 182 riveted thereto. Each locking member 180 is preferably formed of resilient material and is provided adjacent one end with a protuberance 184 projecting inward from said member. Said protuberance is adapted to be disposed in an aperture 186 formed in said ear. The other end of the locking member is enlarged and is formed with a keyhole shaped slot or aperture 188, the larger portion of which is adapted to receive the shank of the pivot pin 174 while the smaller portion thereof is adapted to receive the groove 178 of the pivot pin.

When the pivot pins are inserted within the aligned apertures 159, the locking member 180 is disposed in the dotted line position illustrated in Fig. 8. The larger portion of the aperture 188 is then aligned with the apertures 159 for receiving the shank of the pivot pin 174. The head 176 of said pin will limit the insertion of the pin into said apertures. When the head 176 has been moved into abutment with locking member 180, said locking member is then moved to the full line position illustrated in Fig. 8 to dispose the perimeter of the smaller portion of aperture 188 in the groove 178 of the pivot pin. Simultaneously, the protuberance 184 will then be disposed in the aperture 186 to secure the locking member in locking position to prevent accidental removal of the pivot pin 174 from the apertures of the ears of the now pivotally connected end links.

By simply pivoting each locking member 180 to the dotted line position indicated in Fig. 8, the pivot pins 174 may be quickly and readily removed, following which the ends of the feeder may be separated for purposes of removing the same from the magazine. Such movement of the locking member will obviously cam the protuberance 184 from engagement with the aperture 186.

The feed channel 16 is provided with a pair of parallelly spaced stripper cams 190 respectively provided with cartridge camming surfaces 192. The upper surface of each of the stripper cams comprises a guide surface for the feeder 154 while moving through the feed channel. As is shown in Fig. 10, the cams 190 are adapted to pass between the side flanges of the feeder links and the edges of springs 172 which are carried by each link. As a loaded feeder moves in feeding direction, or toward the right as viewed in Figs. 5 and 6, the narrow pointed ends of the stripper cams nearest the entrance end of the feed channel engage between the base portions of each link and the outer surface of the cartridge carried thereby, whereby continued movement of the feeder and cartridges in feeding direction will cause the camming surfaces 192 to cam the cartridges from their normal position in the notches in each link. The shape of the cam surfaces 192 is such that each cartridge will be entirely disengaged from the feeder link normally carrying the same when said cartridge reaches a position substantially

transversely midway of the breech casing 12, which position is illustrated by the cartridge 80 diagrammatically shown in Fig. 5.

The feeder and cartridges contained therein are moved in feeding direction around the guideway of the magazine by a feed slide 194 which is slidably mounted for transverse movement in feeding and retrograde direction in the upper portion of the feed channel. Said feed slide is slidably mounted in guideways 195 respectively provided in opposite sides of the feed channel, as shown in Fig. 3. Said feed slide is provided with a suitable slot 196 adapted to accommodate a depending lug carried by the feed slide lever 198 as shown in Fig. 7. The lever 198 is automatically actuated by breech mechanism included in the feed box and breech casing of the firearm, which breech mechanism is moved automatically upon the firing of cartridges in the firearm.

Said breech mechanism is not completely illustrated in detail in the description of the present invention inasmuch as it constitutes no part thereof. However, said Browning Patent 1,525,065 and said Webb Patent 2,375,452 clearly and fully illustrate the mechanism serving to automatically actuate the feed slide lever 198 and, for a complete description of said operating mechanism, attention is directed to said patents.

The lever 198 primarily serves to intermittently reciprocate the feed slide in feeding direction while a biasing lever 200 is provided with a depending lug adapted to engage a slot 202 in the feed slide for insuring the movement of the feed slide in retrograde direction at the completion of each feeding movement or stroke thereof. Details of the biasing lever 200 will be found in a copending application, Serial No. 377,818, filed February 7, 1941, now Patent No. 2,372,462 dated March 27, 1945, in the name of George Webb. For further details of the construction and operation of said biasing lever, attention is directed to said application, since said biasing lever forms no part of the present invention.

The feed slide illustrated in the present application is similar to that shown in said Webb Patent 2,375,452. However, the present feed slide is provided with a feeder engaging feed pawl 204 which is different from the plurality of feed pawls illustrated in said patent. Feed pawl 204 is mounted in a suitable recess formed on the underside of said feed slide and is pivotally carried by a horizontal pin 206 extending across said recess in the feed slide. Said pawl is provided with a feeder engaging tooth 208 adapted to successively engage one wall of feed recesses 170 disposed between the adjacent ends of the links 156. Said pawl is also normally biased by spring 210 in a direction to be disposed successively into said feed recesses.

Feed pawl 204 may be raised from engagement with the feed recesses, when the cover 15 is in open position, by means of a manually engageable handle or button 212 extending upward from said pawl. The handle 212 projects through and extends above the upper surface of the feed slide, said feed slide being provided with an aperture 214 to accommodate said handle.

A holding pawl 216 is also disposed in said recess in the underside of the feed slide and is pivotally mounted therein on pin 206. As shown in Fig. 7, the feed pawl 204 is provided with a pair of legs which are pivoted to the pin 206, one of said legs being narrower than the other to provide a space to accommodate the pivotally

mounted end of the holding pawl 216. Said pivoted end of the holding pawl is narrower than the toothed end and said holding pawl is also provided with a portion 218 which overlies one corner of the feed pawl 204, whereby as the feed pawl is raised from engagement with the feeder by the handle 212, said one corner of the feed pawl engages the overlying portion 218 of the holding pawl and continued upward movement of the feed pawl serves to also raise the holding pawl from engagement with said feeder. Further details and the function of the holding pawl will be presently described.

The feed box of the firearm is provided with means to control the movement of the feeder through the feed channel, said means being particularly adapted for use when the firearm is being used without the magazine herein described being secured thereto. Said feeder movement controlling means comprises a retaining dog 220 pivotally carried by a bracket 222 fixed at its opposite ends to the sides of the feed box. Said retaining dog is provided with a tooth 224 adapted to extend into the successive spaces between the upper ends of the side flanges of adjacent links to prevent accidental retrograde movement of the feeder while being fed through the feed channel. Retaining dog 220 is normally spring-pressed in feeder engaging direction by means not shown but said means are similar to those illustrated in said Webb Patent 2,372,462 for actuating the retaining dog illustrated therein. When the feeder is moving in feeding direction, said tooth 224 is automatically cammed from engagement with the edges of the links defining the spaces between the links of the feeder.

A stop dog 226 is also pivotally carried by bracket 222 and is provided with a tooth 228 adapted to be disposed in the successive spaces between the upper portions of the side flanges of adjacent feeder links to normally prevent further movement of the feeder in feeding direction after the feed slide has completed each intermittent feeding movement of the feeder. Stop dog 226 is also normally urged in feeder engaging direction by means not shown but which means are similar to those illustrated in said Webb Patent 2,372,462 for biasing a similar stop dog.

In order that stop dog 226 may be moved from its position shown in Figs. 7 and 7^a, so as to permit the next intermittent feeding movement of the feeder in feeding direction, the feed slide is provided with a horizontally disposed cam 230, the left end of which, as viewed in Figs. 7 and 7^a, engages said stop dog 226 at 227 substantially at the end of the movement of the feed slide in retrograde direction, whereby the tooth 228 of said dog is moved forward in the feed box from the position shown in Figs. 7 and 7^a, wherein said tooth is disposed in the space between said feeder links. Upon the commencement of the next movement of the feed slide in feeding direction, the space last receiving said stop dog tooth will be moved with the feeder past the position shown in Fig. 7 before the cam 230 clears said stop dog to permit said dog to be subsequently biased into position to engage the edge of the side flange of the next succeeding link. The successive normal feeding movements of the feeder by the feed slide are thus not obstructed by said stop dog. Said stop dog 226 is to be distinguished from a stop pawl carried by the magazine, which stop pawl is to be presently described.

As has been partially described in the foregoing, the retaining dog and stop dog described

immediately in the foregoing are adequate to control the movement of a feeder containing a small number of cartridges and even as many as fifteen or so, particularly when said cartridges are being fed to the feed channel in a substantially horizontal direction so that the force of gravity does not assist in moving the cartridges in feeding direction. However, when a magazine carrying cartridges considerably exceeding fifteen in number is attached to the firearm, and particularly where said cartridges are of the larger size adapted to develop muzzle velocities of approximately 3,000 feet per second, the weight of the cartridges moving downward on the left hand side of the magazine particularly, as viewed in Fig. 1, tends under some circumstances to automatically move the feeder in feeding direction through the feed channel irrespective of the feeding movement thereof by the feed slide, whereby overfeeding of the feeder may occur so as to prematurely strip cartridges from the feeder and jam the prematurely stripped cartridges in the breech casing or the chamber of the firearm. The force of gravity acting upon said cartridges moving downward in the left hand side of the magazine is also sometimes sufficiently great to cause a too rapid movement of the feeder in feeding direction, whereby not only may premature stripping of cartridges take place, but said feeder may be moved too rapidly for the stop dog 226 to engage in the spaces between the adjacent feeder links and prevent overfeeding of the feeder.

Such malfunctions or misfunctions of the feeding mechanism of the firearm have been found to exist only when a magazine of the type illustrated is used with said firearm and wherein cartridges of said larger size are contained. Accordingly, in order that such malfunctions or misfunctions may be prevented and to insure that the feeder may be positively stopped at the end of each successive movement thereof in feeding direction, the present magazine has been designed to include a bell crank 232 pivotally mounted on a transverse shaft 234 extending between and carried by end members 24 and 26. One leg or arm of the bell crank comprises an auxiliary stop pawl 236 adapted to coact successively with feed recesses 170 of the feeder. The other leg or arm 238 of the bell crank is adapted to be engaged by the left end of the feed slide, as viewed in Fig. 6. Stop pawl 236 is normally biased in feeder-engaging direction by a coil spring 240 which is coiled about the shaft 234 and respectively engages with its opposite ends the stop pawl 236 and an aperture 242 formed in plate 114.

The outer end of stop pawl 236 is provided with a tooth 244 which is directly and successively received within the successive feed recesses 170 substantially at the completion of each movement of the feeder in feeding direction. More specifically, said tooth 244 is received within the notches 168 provided in the ends of each link. While the feeder is moving in feeding direction, the tooth 244 of the stop pawl 236 slidably rides on top of the feeder links and, when the next succeeding feed recess moves into position to receive tooth 244, the strength of the spring 240 is sufficient to insure that said tooth will positively be received therein, regardless of the force of gravity which may reasonably be expected to prevail under any circumstances to act upon the feeder, or the speed with which the feeder may be moving under said circumstances. In other

words, even when the feeder is moving too rapidly for stop dog 226 to engage in the space between the feeder links, the tooth 244 of stop pawl 236 will nevertheless engage the walls of the next succeeding feed recess 170 to effect stopping of the feeding movement of the feeder.

Not only will the stop pawl 236 coact with one of the feed recesses 170 to positively stop the movement of the feeder in feeding direction, but said stop pawl will remain in engagement with said feed recess substantially during the entire movement of the feed slide in retrograde direction. When the feed slide is substantially at the end of its movement in retrograde direction, the left end of the same, as viewed in Fig. 6, engages the leg 238 of the bell crank 232 to remove the tooth 244 of stop pawl 236 from the feed recess receiving the same. At the time said stop pawl tooth is thus removed from said recess, the tooth of feed pawl 204 is in engagement with the feed recess 170 to be next engaged thereby and, additionally, the tooth of holding pawl 216 is within the feed recess 170 next preceding that engaged by said tooth of feed pawl 204, whereby the holding pawl 216 will prevent movement of the feeder in feeding direction notwithstanding the fact that the stop pawl 236 has been disengaged from the feeder.

It will thus be seen that the stop pawl 236 and the holding pawl 216 jointly serve to positively prevent overfeeding of the feeder at all times, regardless of the position in which the feed slide may be and also regardless of whether or not the function of the firearm has been such that the stop dog 226 has or has not functioned.

After the feed slide has returned to starting position, as indicated in Fig. 6, for the purposes of engaging the next succeeding link of the feeder to be fed through the feed channel, the feed pawl 204 coacts with a feed recess 170 and holding pawl 216 coacts with the next preceding feed recess. During the next successive intermittent feeding movement of the feed slide and feeder, the holding pawl 216 will prevent any appreciable relative movement between the feed slide and feeder during substantially the entire feeding movement. Substantially at the end of said feeding movement, and at which time stop pawl 236 is in position to coact with its next engageable feed recess, the tooth of holding pawl 216 is removed from its last engaged feed recess, during the last portion of movement of the holding pawl in feeding direction, by releasing or disengaging means 238' carried by the magazine 55 adjacent the exit end of the feed channel.

Disengaging means 238' comprises a bracket 240' secured to plate 116 by suitable bolts 242'. Bracket 240' is horizontally bored to receive a slideable plunger 245 provided with a shaft 246 60 surrounded by a spring 248 which is also contained in the bore of said bracket. As viewed in Fig. 6, spring 248 normally biases the plunger 245 toward the left or holding pawl engaging direction and movement of said plunger in said 65 direction is limited by engagement of a cotter pin 250, disposed in the outer end of shaft 246, with the right-hand end of bracket 240'. The end of the plunger 245 nearest the feed channel is provided with a cam face 252 adapted to engage with a cam face 254 provided on the outer end of the tooth of holding pawl 216. After 70 initial engagement of cam face 254 of the holding pawl 216 with the cam face 252 of the plunger 245, continued movement of the holding pawl in 75 feeding direction will serve first to raise said

pawl from engagement with said feed recess 170. Further continued movement of the holding pawl in feeding direction after said disengagement will serve to also move plunger 245 toward the right a short distance, as viewed in Figs. 5 and 6, to substantially the position shown in Fig. 5. Such movement of the plunger will compress spring 248.

At the commencement of the movement of the feed slide in retrograde direction, the biasing force of spring 248 will serve to retain the cam faces of the plunger and holding pawl in co-engagement and also maintain the holding pawl tooth out of engagement with the feeder while said plunger is moving from the position shown in Fig. 5 to substantially that shown in Fig. 6. Said amount of movement is sufficient to move the holding pawl clear of and past the feed recess 170 last engaged thereby. When said feed recess has been cleared by the holding pawl and the movement of the plunger 245 in retrograde direction has been arrested by cotter pin 250, the cam faces 252 and 254 will become disengaged and the tooth of the holding pawl, which is normally biased by a spring 256 in feeder engaging direction, will then engage the upper surface of the next link and ride on the same toward the left, as viewed in Figs. 5 and 6, until the feed recess 170 at the left end of said link is reached for receiving the tooth of said holding pawl. It will thus be seen that the plunger 245 not only serves to disengage the holding pawl from the feed recess but also acts to clear said holding pawl of said feed recess in order that said holding pawl may move in retrograde direction to coact with the next succeeding feed recess.

When the firearm is being automatically fired, the movement of the feed slide and the various dogs and pawls controlled and actuated thereby is very rapid. This is particularly true with regard to the movement of stop pawl 236. Notwithstanding the fact that said pawl is normally biased in a direction to engage the feeder, when said pawl is raised from engagement with said feeder by the end of the feed slide engaging leg 238, the outer end of the stop pawl 236 is raised very rapidly upward between the discs comprising the sides of reel 86 and the momentum of the movement might be sufficient to overcome the force of spring 240 and move said outer end sufficiently high to interfere with one of the rods 94 holding the discs of reel 86 in spaced relationship were it not for the inclusion of drum 103 in reel 86, which drum will thus prevent any interference between the stop pawl 236 and the rods 94.

The pair of dogs 142 are primarily adapted to assist retaining dog 220 to prevent movement of the feeder and cartridges contained therein in retrograde direction. Dogs 142 are biased upward, whereby their free ends are adapted to engage between succeeding cartridges. The disposition of the pivot for said dogs, the dogs, and the cartridges, is such that movement of the cartridges in feeding direction will automatically cam said dogs downward past the next succeeding cartridge and spring 159 will then automatically bias said dogs upward into engagement with the other side of said next succeeding cartridge and the adjacent side of the next following cartridge. Said disposition of the enumerated members, however, is also such that retrograde movement of the cartridges and feeder will be prevented by said dogs 142. In the event it is desired to manually move the feeder and cartridges

in retrograde direction, said dogs 142 may be readily moved from their operative position by manipulating handle 152 to move said dogs downward.

The magazine may be loaded with cartridges by inserting the same in the notches 160 of the side flanges of the links comprising that portion of the feeder 154 which is disposed between the upper edges of plates 120 and 122. Loading of this portion of the magazine is feasible inasmuch as the guideway defined by flanges 77 and 78 opens outward of the magazine at this portion thereof. Even if plate 122 is removed from the magazine, the flange 139, if embodied in the magazine, extends upward a distance substantially equal to the length of plate 122 and will thus prevent insertion of cartridges in that portion of the feeder disposed opposite said flange. Plate 120, however, should be removed to permit loading of that portion of the feeder which is disposed opposite said plate. Inasmuch as plate 140 is not adapted to be readily removed from the magazine, that portion of the feeder extending between the entrance side of the feed channel and the upper end of plate 122 or flange 139 has to be loaded by first loading the other exposed portions of the feeder and then moving said loaded portions around the guideway to dispose said loaded portions opposite plate 140 and flange 139. Following this, the remaining unloaded and exposed portions of the feeder may be readily loaded with cartridges, whereby the magazine will finally be fully loaded. That portion of the feeder which is opposite plate 120 is normally the last to be loaded inasmuch as said portion is adjacent the exit end of the feed channel. Plate 120 is replaced and locked in operative position after said portion of the feeder has been loaded, the magazine then being fully loaded.

In view of the fact that the stop pawl 236 or the holding pawl 216, or both, will normally serve to prevent free movement of the feeder around the guide channel therefor and through the feed channel, the complete loading of the magazine in the manner above described is achieved by providing auxiliary charging means for manually operating the feed slide.

Said manually operable means comprises a crank-like handle 269 pivoted at 262 and having a hand engageable member 272. A spring 304 biases the member 269 for movement in the clockwise direction. Manual oscillation of the member 268 causes reciprocation of the feed slide and the intermittent advancement of the feeder through the feed channel. The details of the charging means do not constitute any part of the present invention and further description is unnecessary.

When it is desired to remove the magazine from the firearm for any purpose, the pivotally connected end links of the feeder are first disconnected by manipulating the locking members 180 disposed on opposite sides thereof and then removing said feeder and any cartridges contained therein from the magazine and feed channel. The quick detachable locking mechanisms 44 are then removed from the end members to permit the separation of the upper portions of the bipartite parts forming the frame-like magazine. The lower portions of said two parts are then separately disconnected from the respective sides of the feed box to which they are normally held attached by the quick detachable securing means described in the foregoing. The firearm may then be used with any other

suitable type of magazine or feeder. The present feed slide carrying the holding pawl 246 should also be removed unless said feed slide is to be next used in combination with a magazine having a releasing means similar to holding pawl releasing means 238' described above. Such feed slide may, for example, be replaced by one similar to that illustrated in said Webb Patents 2,375,452 and 2,372,462.

From the foregoing, it will be seen that the present invention provides a magazine embodying improvements which render the magazine adapted to operate in a completely satisfactory manner under all conditions and while holding larger sized cartridges than those heretofore carried by similar magazines. Notwithstanding the added weight of said larger sized cartridges, the details of the invention embodied in the present magazine and feeder operating and control mechanism are such that the feeder and cartridges are moved around said magazine with a minimum of friction and the intermittent movements of the feeder and cartridges to and through the feed channel are positively controlled during all phases of such movement so that no substantial overfeeding or retrograde movement of the feeder may take place.

The various parts of the magazine and feeding mechanism are designed to produce a minimum of weight in the assembled magazine while sacrificing no essential strength or rigidity in said magazine. Furthermore, the magazine and the various feeder movement controlling members are readily accessible and removable from the firearm to which they are secured, in most instances, by quick detachable means. The instant feeder is designed so as to be durable yet simple and the same may also be inexpensively manufactured. For the most part, the quick detachable means for securing the ends of the feeder together and for securing the magazine to the firearm are carried at all times either by the feeder or by the magazine, whereby they will not become misplaced or lost when not being used. The invention also includes means for easily and readily manually advancing the feeder through the magazine.

In the foregoing, descriptive terms used to denote position and/or direction such as horizontal, vertical, forward, rearward, downward, upward, depending, and the like, are used with respect to the firearm and magazine when mounted in the "normal" position which is that illustrated in Figs. 1, 3 and 4 when the sheets containing the same are disposed vertically. The "forward" end of the firearm is the muzzle end or that end from which the barrel projects. Similarly, the rearward end is the end opposite the forward or muzzle end and is also the end adjacent which the manually operable means 260 are mounted. Also in the foregoing, the term "transverse" is used to denote the direction in which the feed slide and feed channel extend with respect to the longitudinal axis of the firearm. Said descriptive terms are therefore to be considered in the same relative sense with respect to said "normal" position of the firearm, regardless of the position in which the firearm, magazine, and other features of the invention may be disposed at any given instant.

It is to be understood that the term "forward" when used as descriptive of the direction of movement of the feeder and the feed slide, together with the parts carried by the feed slide, connotes movement in the direction of movement of the

feeder as cartridges are being fed to the firearm during normal functioning; and with specific reference to the embodiment of the invention illustrated, it has reference to movement of the feeder in a counter-clockwise direction as viewed in Fig. 5. Similarly the term "retrograde" when used as descriptive of the movement of the feeder, the feed slide (together with the parts carried by the feed slide) and the withholding pawl disengaging means 238', is to be understood as connoting movement of a direction opposite to that of forward, as above defined, or clockwise when considered in connection with the illustrated embodiment of the invention as viewed in Fig. 5.

15 While the invention has been illustrated and described in its preferred embodiment and has included certain details, it should be understood that the invention is not to be limited to the precise details herein illustrated and described

20 since the same may be carried out in other ways, falling within the scope of the invention as claimed.

What we claim is:

1. In an automatic firearm having a feed channel to receive cartridges and a cartridge feeder provided with spaced feed recesses the combination of a feed slide reciprocably mounted for movement in feeding and retrograde directions and provided with a feed pawl successively engageable with the feed recesses of a feeder to intermittently move said feeder and cartridges through said feed channel in feeding direction, a holding pawl on the said feed slide successively engageable with the feed recesses of a feeder for substantially the full lengths of the intermittent feeding movements thereof to positively prevent movement of the feeder in the feeding direction with respect to the slide, and means engageable with said holding pawl substantially at the end of each intermittent movement of the feed slide in feeding direction to disengage said holding pawl from a feed recess engaged thereby, said disengaging means serving to maintain said holding pawl disengaged from the last engaged feed recess for at least the first portion of the retrograde movement of the feed slide and the attached holding pawl.

2. In an automatic firearm having a feed channel to receive cartridges and a cartridge feeder provided with spaced feed recesses, the combination of a feed slide reciprocably mounted for movement in feeding and retrograde directions and provided with a feed pawl successively engageable with said feed recesses of a feeder to intermittently move said feeder and cartridges through said feed channel in feeding direction, a holding pawl on the said feed slide successively engageable with the feed recesses of a feeder for substantially the full lengths of the intermittent feeding movements thereof to positively prevent movement of the feeder in the feeding direction with respect to the slide, reciprocably movable disengaging means adapted to engage and be moved with said holding pawl during the latter portion of each intermittent movement of the feed slide in feeding direction and serving during such movement to disengage said holding pawl from a feed recess engaged thereby, and biasing means urging said disengaging means in retrograde direction during the first portion of each retrograde movement of said feed slide and the attached holding pawl to maintain said holding pawl disengaged from the last engaged feed recess until after said recess has been cleared thereby.

3. In an automatic firearm having a transverse feed channel to receive cartridges and a cartridge feeder provided with a plurality of spaced feed recesses, the combination of a feed slide reciprocably mounted for movement in feeding and retrograde directions in said feed channel and provided with a feed pawl adapted to successively engage said spaced feed recesses in a feeder to intermittently move said feeder and cartridges through said feed channel in feeding direction, a holding pawl carried by said feed slide and adapted to successively engage the feed recesses of a feeder for substantially the full lengths of the intermittent feeding movement of said feeder, the said holding pawl serving in conjunction with the feed pawl to prevent any appreciable relative movement between said feeder and feed slide during each intermittent feeding movement and the said holding pawl having a cam face thereon, and a reciprocably mounted disengaging member provided with a cam face positioned to engage the cam face of said holding pawl substantially at the end of each feeding movement thereof to disengage said holding pawl from a feed recess engaged thereby, said disengaging member being movable with said feed slide and holding pawl at the commencement of retrograde movement thereof at least a sufficient distance to clear the holding pawl of said last engaged feed recess.

4. In an automatic firearm having a feed channel adapted to receive a feeder and cartridges carried thereby, the combination of a feed slide adjacent the feed channel and automatically reciprocable in the feeding direction and in the retrograde direction in timed relationship with the functioning of the firearm, means on the feed slide automatically engageable with a feeder in the feed channel to positively lock the said feeder in substantially fixed relationship with the slide during the major portion of each feeding movement of the latter, and means for automatically releasing the said locking means near the end of each feeding movement to permit the slide to move in the retrograde direction independently of the feeder.

5. In an automatic firearm provided with a transverse feed channel adapted to receive cartridges and a cartridge feeder having a plurality of feed recesses spaced longitudinally thereof, the combination of a feed slide reciprocably mounted in said feed channel for movement in feeding and retrograde directions and having a feed pawl successively engageable in spaced feed recesses of a feeder for intermittently feeding said feeder and cartridges through said feed channel, means automatically operable by the functioning of the firearm to reciprocate said feed slide, a magazine removably attached to said firearm and adapted to hold a cartridge feeder and cartridges in position to be fed to said feed

channel, and an auxiliary stop pawl mounted on said magazine and removable therewith from the firearm, the said stop pawl being adapted to engage a feeder at the completion of each intermittent feeding movement thereof to prevent further movement of the feeder in feeding direction while said feed slide is moving in retrograde direction.

6. In an automatic firearm provided with a transverse feed channel adapted to receive cartridges and a cartridge feeder having a plurality of feed recesses spaced longitudinally thereof, the combination of a feed slide reciprocably mounted in said feed channel for movement in feeding and retrograde directions and having a feed pawl successively engageable in spaced feed recesses of a feeder for intermittently feeding said feeder and cartridges through said feed channel, means automatically operable by the functioning of the firearm to reciprocate said feed slide, a magazine removably attached to said firearm and adapted to hold a cartridge feeder and cartridges in position to be fed to said feed channel, an auxiliary stop pawl mounted on said magazine adjacent said feed channel of the firearm and removable therewith from the firearm, the said stop pawl being adapted to engage a feeder at the completion of each intermittent feeding movement thereof to prevent further movement of the feeder in feeding direction while said feed slide is moving in retrograde direction, and means movable by said feed slide substantially at the completion of the retrograde movement thereof to disengage said auxiliary stop pawl from a feeder.

GEORGE WEBB.
